UNITED STATES PATENT OFFICE

EUGENE A. LEARY, OF CINCINNATI, OHIO

WHEEL STOP

Application filed December 30, 1930. Serial No. 505,491.

The present invention relates to a bumper or stop for attachment to railway rails and has for its primary object the provision of a simple inexpensive construction which occupies a minimum of track space.

Another object is to provide a device which is of one-piece cast construction which requires no machining and which is effectively retained in position by means of an ordinary rail spike such as may ordinarily be found in abundance around terminals and yards.

Another object is to so fashion the contact or bumper surface of such a device with an arc of about 20% greater radius than the 15 contacting portion of the wheel of a vehicle so that the thrust of such wheel on the stop will direct the impact into a downward direction on the stop so that greater binding of the stop on the rail occurs.

These and other objects are attained by the means described herein and disclosed in the accompanying drawings, in which:

Fig. 1 is a side elevational view of one form of the device, part being broken away, 25 and in operative relation with a rail and car wheel.

Fig. 2 is a view on line 2—2 of Fig. 1.

Fig. 3 is a side elevational view of a preferred form of the device, part being broken 30 away.

Fig. 4 is a view taken on line 4—4 of Fig. 3.

Fig. 5 is a view showing a modification of the device shown in Figs. 3 and 4.

Fig. 6 is a view taken on line 6—6 of Fig. 5.

The device of the present invention consists of a one-piece casting, preferably of steel comprising an elongated body 9 of a 40 cross section larger than the rail to which it is to be attached but generally conforming to the shape thereof and having a longitudinal way 10 therethrough which slidably receives the head 11 of the rail 12. The 45 body 9 thus provides a pair of curved arms 13 and 14 which embrace the rail head and web. A tapered way 15 extends from the rear of the device toward the front and is substantially closed by the top face of the 50 rail when the device is mounted thereon.

Into this way an ordinary rail spike 16 is driven. The rail and the stop or bumper being of much harder steel than the spike, it is possible to very solidly and effectively produce a rigid binding of the arms 13 and 55 14 on the under side of the rail head. A number of notches are formed on the top wall of way 15 so that the intermediate tooth-like edges which result may bite into the rail spike 16 and allow the metal of the spike to 60 spread slightly into the notches thereby increasing the binding action. The short edge 18 of the spike head sliding along the top face of the rail under hammer blows facilitates the initial wedging of the body 9 to 65 the rail head.

Integral with body 9 is the stop or bumper indicated generally as 19 which is conveniently apertured at 20 in order to grasp it or to receive a crow bar when several devices are 70 being carried by two men. This aperture also materially reduces the weight without limiting the operative strength of the device. The front face 21 is formed on a radius about twenty percent greater than that of the car 75 wheel and the top 22 tapers down toward the rear end.

The effect of this curvature of the impact face is to stop a car even though it strikes the stop with considerable force. The tendency of a wheel to ride up the curved face 21 is translated into a forward counter force on the wheel which at most would spin the wheel.

As previously indicated the device as 80 shown in Fig. 2 is of the preferred form for general use. In Fig. 1 it will be noted that the plates 13 and 14 are provided with bolt holes to receive the usual fish plate bolts 23. 85 In this construction the usual fish plates at the junction of two rails are eliminated since arms 13 and 14 replace them.

In the construction shown in Fig. 5 an arcuate cavity 24 is provided at the end of the 90 way 15 so that the end of a spike 16 may be upset as at 25 to provide a permanent type of wedging and clamping to the rail head 11. This form of device can be removably mounted just as that shown in Fig. 3, if the spike 100

is not driven far enough to upset the end of the spike.

The advantages of having a single piece, relatively rough casting which employs merely the ordinary rail spike as a securing wedge will be apparent. The devices employ no excess metal and are therefore as light as is practicable. The use of the rail spike as a wedge eliminates the necessity of packing and shipping any special hardware and reduces the cost to a minimum because discarded old spikes may be used if desired.

What is claimed is:

1. A wheel stop for railway rails comprising a one piece cast metal member having a longitudinal way therethrough for slidably receiving the head of a rail, the way having a tapered enlargement at one end for receiving an ordinary rail spike, the cast member having a tapered upwardly extending portion arcuately cut away at the end opposite the spike receiving way.

2. A wheel stop of the class described comprising an elongated metal member having a longitudinal way for slidably receiving the head of a railway rail, said way having a tapered way communicating therewith at one end of the member for receiving a rail spike to wedge said metal member into binding relation with the rail head.

3. A one piece stop member for railway rails comprising a substantially triangular portion, open at the center and having one external face arcuately cut away on a radius approximately twenty percent greater than the radius of a railway car wheel, integral slotted means for slidable entry of a rail head and a wedge member for binding said stop at the end opposite the arcuate face.

4. In a car stop of the class described the combination of an elongated metal body having a substantially T-shaped slot extending longitudinally therethrough for slidably receiving the upper portion of a railway rail, said body having a communicating open way therein for receiving a rail spike and guiding it into frictional binding with a rail and body.

5. In a car stop of the class described a one piece member slotted to embrace the head of a rail and adjacent sides of the web, the lower portions of the member being perforated to serve as fish plates, said member also having a tapered way adapted to receive a rail spike in horizontal frictional binding relation to the top face of the rail head, and an integral portion extending above the top of the rail head and presenting an abutment for a vehicle wheel on said track.

6. In a car wheel stop of the class described the combination of a one piece body having a T-shaped way and a communicating notched tapered way at one end, the T-shaped way receiving a rail head, the tapered notched way and the rail head provid-

ing a tapered pocket for the reception of a driven wedge such as an ordinary rail spike.

7. In a car wheel stop of the class described, the combination of a one piece member having an elongated T-shaped way therethrough for the reception of a rail head, sidewalls on opposite sides of the said slot having perforations and serving as fish plates for joining adjacent ends of a pair of rails, bolts extending through said fish plate portions and rails, the body having a notched tapered way for receiving a driven rail spike to effect clamping of the stop and rail opposing sliding due to impact of a vehicle wheel on said stop.

8. In a device of the class described a wheel stop body longitudinally channelled along the bottom to conform to a railway rail head, said body having a tapered groove and an arcuate cavity both communicating with the way and adapted to be closed along one side by the rail head to form a passage for a rail spike, the cavity serving to receive the upset metal of the rail spike when driven into the way whereby to preclude withdrawal of the spike.

In testimony whereof, I have hereunto subscribed my name this 23rd day of December, 1930.

EUGENE A. LEARY.
